UNITED STATES PATENT OFFICE.

SALOMON M. MEYENBERG, OF PATERSON, NEW JERSEY.

DESIGN FOR A VEIL.

Specification forming part of Design No. **7,632**, dated August 11, 1874; application filed July 25, 1874.
[Term of Patent 3½ years.]

To all whom it may concern:

Be it known that I, SALOMON M. MEYENBERG, of Paterson, in the county of Passaic and State of New Jersey, have invented a new and original Design for a Veil, of which the following is a specification:

The nature of my design is fully represented in the accompanying photographic illustration, to which reference is made.

The object of my invention is to produce an elegant and striking design for a veil; and it consists, mainly, in the chenille trimming and border lining of a silk or other veil.

A represents the veil, preferably of sewing-silk, with or without a satin border, which is provided with trimmings or fringes B of chenille, applied along the edges of the same. The ends of the chenille trimming B are produced in a different color from the body or upper part adjoining the veil, any color suitable to the color of the veil being applicable thereto, so that a great variety of effects can

be produced with the same arrangement of the fringes. An additional interior chenille lining or stripe, C, is run at some distance from the edges of the veil, it being prepared in part with the same color as that of ends of the fringes B, so as to alternate with the other parts having the color of the body of the trimmings. This gives a neat and striking ornamentation in harmony with the veil and the outer trimmings, and produces a tasteful and elegant design for veils.

I claim as my invention—

The design for a veil formed with chenille trimmings or fringes, having differently-colored ends, and a border of chenille stripes, prepared in corresponding colors, substantially as shown and described.

SALOMON M. MEYENBERG.
